UNITED STATES PATENT OFFICE

CHARLES ERNEST COWDIN, OF PORTLAND, OREGON, ASSIGNOR TO COWDIN COMPANY,
A CORPORATION OF OREGON

WRITING DEVICE

Application filed November 12, 1929. Serial No. 406,694.

My invention relates to tables generally, but particularly to card tables, wherein is incorporated a recording device comprising a platen and a partly overlapping frame whose upper face is made flush with the table-top and which is combined with means for feeding, little by little, in either direction, a strip of paper from a source of paper supply provided below the surface of the table. 10 A broad object of my invention is to provide in any table-top or desk a device that will be available when needed for the making thereon of any entry in writing, but which presents no obstruction at any time to the free 15 use of the table-top for the purpose intended for it.

The nature of my invention, as above described, lends to it a utility when combined with any office desk or table-top, but it has 20 a special value in card tables as providing an ever ready but unobstructive, renewable means for keeping score of any game while it is being played thereon.

What constitutes my invention will be hereinafter described in detail and succinctly defined in the appended claims.

In the accompanying drawings, which constitute a portion of this specification,

Figure I is a longitudinal vertical section 30 of a preferred form, of my recording device, set in a table-top flush with the upper surface thereof, a portion only of the table-top being shown, and the recording device being shown as provided with a substantially full paper 35 supply.

Figure II is a top plan view of the recording device shown in Figure I, detached from the table-top.

Figure III is a section on the line III—III 40 of Figure I.

Figure IV is a perspective view, looking from above obliquely downward upon the top of a folding card table which is presented as an example of any ordinary or preferred 45 type of its class, but comprising, in one corner of it, for example, the recording device shown in the preceding figures.

Referring to the numerals on the drawings, 1 indicates a table-top, that term being used 50 in the broad sense to designate any sort of a

horizontal supporting member superposed above a floor.

An opening in the top 1 is made to accommodate within it an assemblage of members constituting a recording device which comprehends a horizontal frame-top 2 that fits snugly within a shallow recess 3 provided for it in the top about said opening, and whose upper surface is flush with the surrounding surface of the top. 55

The frame-top 2 is shown in plan view complete in Figure II. Attached thereto, on its under side and spaced apart therefrom a sufficient distance to accommodate with slip fit, a strip 4 of paper of suitable dimensions, is a platen 5 whose entire area is encompassed by the frame-top 2 which covers it in part, and which marginally overlaps the opposite sides of the platen. At one end of said frame-top the platen is provided actually or in effect, 60 by a shaping of the table-top, with an upturned curved lip 6 which is formed so as to present no obstruction to the movement, back and forth in either direction, of the strip 4 within the space defined between the frame-top 2 and the platen 5. 65

The edge of the lip 6 might end flush with the face of the frame-top 2, but I prefer to provide, as a finish for it, a horizontal extension 7 that is made and set in the table-top 70 flush with the top of the frame-top 2 as well as with the upper surface of the table-top 1, as is clearly illustrated in plan in Figure I. 75

The frame-top 2 is preferably provided with two fixed depending parallel side plates 80 9, each having a downward extension plate 10 for the joint accommodation in alined bearing apertures of a rotative shaft 11, upon which the strip 4 is rolled so as to constitute a convenient source of paper supply that will 90 be, subject to replacement, adequate for requirements from time to time. At one end 12, the shaft 11 may be of reduced diameter 95 in order to provide at that end a longitudinally limited bearing that is adapted to rotate within the bearing aperture in one of the plates 10. A bearing aperture of capacity to take in the full diameter of the shaft 11 may be provided in the other plate 10. The shaft 11 may be rotatably held in place by a resil- 100

ient keeper 14, fastened to the side of the last named plate as indicated at 15.

Parallel to the shaft 11 is a rod 17 secured at its opposite ends in the plates 9, so that it 5 may serve as a pivotal support for one end of a brake piece 18 that is suspended from it. Its free end, which is preferably curved, makes yielding contact with the cylindrical periphery of the roll 19 into which form the 10 excess length of the strip of paper 4 is wound.

The purpose of the brake action of the member 18 is to provide means for holding the roll 19 yieldingly in a normal position, whereby it may permit motion of the strip 4 15 under tension upon it in one direction, but will remain stationary if that tension is released by movement of the strip 4 in the opposite direction.

The member 18 is, for the purpose specified, 20 spring actuated as by a wire frame 20 having a cross-over intermediate loop 21, and projecting terminals 22. A resilient action is imparted to the loop 21 against the brake piece 18 by aid of spring coils 23 and 24 25 formed about the rod 17. The spring tension of said coils is caused to be exerted by the pressure of the terminals 22 against the bottom of the platen 5, on the one part, and, on the other part, by the pressure of the free 30 end of the member 18 against the periphery of the roll 19. The tension exerted by said coils increases slightly with increase of the diameter of the roll 19, but is operatively effective upon the roll until the strip of paper 35 4, of which it is constituted, is exhausted.

The platen 5 is provided, preferably by the bending of it at its intake end nearer the shaft 11, with a smooth horizontal guide piece 25 which facilitates the free movement of the 40 paper strip 4 in either direction under pressure when properly applied by the thumb or finger of an operator against such portion of its surface above the platen 5 as is exposed within the frame-top 2. At its outlet end the 45 curved lip 6 of the platen 5, or its equivalent as already indicated, facilitates the free outlet without its doubling or bending, of the strip 4.

The roll 19 and its supporting shaft 11 may 50 be disposed at any suitable and convenient place underneath the table-top 1, but, as specified, I prefer, for structural reasons, to provide for their accommodation upon members directly united to the frame-top 2.

In view of the foregoing specification, only 55 the briefest additional description of the operation of my device is deemed to be called for. In that regard, reference particularly to Figure I is invited.

Assuming that the recording device and its 60 equipment are such as that therein shown, the "sight" of the paper strip 4 above the platen within the enclosure of the frame-top 2, may be at any time utilized at will for 65 manually recording on the strip 4 any mem-

orandum desired. Afterwards the strip may be pushed backward or forward into the space provided for it between the platen 5 and the frame-top 2, without occasioning thereby any obstruction upon the surface of the table-top. 70

The occasion for pushing the strip 4 backwardly under the frame-top 2 is seldom likely to arise except when too much of the strip 4 is drawn out of the recording device by inadvertence. In such case the only remedy 75 without waste of paper, is to provide safe and convenient means for returning the excess of paper to the protection afforded by the co-operative effect of the platen 5 and the frame-top 2. 80

What I claim is:

1. In combination with a table top having an opening therein, a frame substantially flush with the top surface of the table and extending inwardly into said opening, a revoluble member beneath said frame, a strip of paper carried by said revoluble member, a platen beneath said frame, the ends of the platen overlapping the adjacent ends of the frame, said strip of paper arranged to pass between the frame and platen below the top surface of the table, and means for deflecting the paper upwardly at a point beyond the end of the frame. 95

2. In combination with a table top having an opening therein, a frame substantially flush with the top surface of the table and extending inwardly into said opening, a revoluble member beneath said frame, a strip of paper carried by said revoluble member, a platen beneath said frame, one end of the platen overlapping the adjacent end of the frame and the other end of the platen extending beyond the frame and deflecting upwardly to a point flush with the top of the table, said strip of paper arranged to pass between the frame and platen below the top surface of the table, and be deflected upwardly at a point beyond the end of the frame. 100

3. The combination with a table top having an opening therein, the top wall of the opening having a marginal recess, a frame fitting in said recess and extending into said opening, the upper surface of the frame being substantially flush with the table top, a platen beneath said frame member and extending into said opening and having its sides overlapping the inner sides of the frame member, said platen having an intake end formed with a depending angularly disposed guide and an outlet end having an upwardly off-set portion positioned beyond the adjacent end of the frame member, a transversely disposed shaft connected to the frame member beneath said platen, and a paper strip roll carried by said shaft, said strip arranged to be directed to the intake end of the platen and across the same beneath the frame member and directed upwardly at the outlet end 115 120 125 130

of the platen, the inner marginal sides of the frame member acting as guides for the adjacent portion of the paper as it passes across the platen.

5 In testimony whereof, I have hereunto set my hand.

CHARLES ERNEST COWDIN.
